CIGARETTE HOLDER AND EXTINGUISHER

John T. Saunders, Chicago, Ill.

Application March 14, 1941, Serial No. 383,437

3 Claims. (Cl. 131—235)

The present invention relates to new and useful improvements in apparatus for holding and snuffing cigarettes and has for its primary object to provide a device of this character embodying a continuous strip of spring metal, bent upon itself at intervals to form a plurality of spring clips within which the cigarette may be positioned, for holding the cigarette, or for snuffing the lighted end of the cigarette, the tension of the side walls of the clip upon the cigarette placed in the clip serves both to retain the cigarette in the clip and prevents burning of the cigarette beyond the point of contact. A further object is to provide a device of this character in which the two intermediate clips, being more rigid, serve to act as a snuffing device when the lighted end of the cigarette is forced within one of the clips where it almost immediately becomes extinguished.

A further important object of the present invention is to provide means for supporting the holder in an upright position in a cigarette tray or upon other supporting surfaces. A still further object is to provide a new article of manufacture which consists of a unitary construction having a pair of cigarette holders, a pair of snuffer clips and a cigar or pipe holder, all of which is of simple and practical construction, which is neat and attractive in appearance, relatively inexpensive to manufacture and otherwise well adapted for the purposes for which the same is intended.

Other objects and advantages reside in the details of construction as more fully hereinafter described and claimed, reference being had to the accompanying drawing, forming part hereof, wherein like numerals refer to like parts throughout, and in which:

Figure 1 is a top plan view,

Fig. 2 is a side elevation view with the ash tray or receiver shown in section, and

Fig. 3 is an edge elevational view showing the holder removed from the ash tray.

Referring now to the drawing in detail, wherein for the purpose of illustration I have disclosed a preferred embodiment of the invention, the numeral 5 designates the cigarette holder generally which is constructed from a single strip of flat spring metal of ribbon form, the strip being bent upon itself substantially at its center as shown at 6 for insertion between a pair of upstanding lugs 7 rising from a rubber suction cup 8 which is adapted to support the holder in an upright position, either upon a flat supporting surface as shown in Fig. 3 of the drawing, or

for supporting the holder within the ash tray or receiver as shown at 9 in Fig. 2. The folded edge 6 of the strip of material may be secured either pivotally or integrally between the upstanding lugs 7 by means of a rivet or pin 10.

The strip of material rises from the anchored portion 6 in slightly outwardly diverging relation to form spaced walls 11, to provide a clip 14 within which a cigar or the stem of a pipe may be inserted, the cigar or pipe stem being wedged between the walls 11 to firmly grip the same.

Additional clip members are formed outwardly at opposite sides of the center clip 14 by bending portions of the strip of material in substantially parallel relation, at intervals to form snuffer clips 15 and holder clips 13, any number of such clips being provided.

Each end of the strip of material extends upwardly to form an end or holder clip 13, defined by side walls 12, the bottom end of the clip 13 being inclined inwardly toward the center clip 14 and extending below the bottom of the intervening or snuffing clip 15.

The intervening snuffing clips 15 are of V-like shape in vertical cross section and have a depth of about only one-half of the depth of the end clips 13 and center clip 14. This is provided so the snuffer clip walls 16 are substantially semi-rigid. Thus, by forcing the lighted end of the cigarette between the walls 11 it will readily be extinguished.

By making the V-like shaped cigarette holder clips 13 longer than the snuffer clips 15, and inclining them inwardly toward the bottom of clip 14, the clips 13 are more-or-less flexible and the outermost walls 12 readily yield outwardly upon slight pressure exerted thereon, such as would be exerted when a cigarette is placed or wedged between the walls 12.

I have provided a straight edge on the upper ends of clips 13 so as to discourage snuffing of the cigarette in these clips. I prefer to have the clips 13 used as cigarette holders, the clips 15 to be used for snuffing the cigarette and the clip 14 to be used as a cigar or pipe holder. As cigarette ashes and other residue from the lighted end of the cigarette are deposited on the side walls of the clips, when a cigarette is snuffed, it is undesirable to place a cigarette which is to be merely "held" in the clip, in such clip as the ashes and residue would be transferred to cigarette paper and it becomes unsightly and foul.

It will now be apparent that by utilizing the present invention cigarettes may readily be extinguished without soiling the finger tips as is

now customary when a cigarette is snuffed in an ordinary ash tray. The cigarette is positively extinguished by using the device of my invention regardless of the clip in which it is placed; hence, dangers of fire resulting from lighted cigarettes being displaced from ash trays is eliminated.

It is believed the details of construction, operation and manner of use and advantages of the device will be readily understood from the foregoing without further detailed explanation.

I claim:

1. A cigarette holder comprising a strip of spring metal in ribbon form, upper and lower return bends provided in said strip of metal to provide a series of clips, and including a centrally disposed clip adapted to receive a cigar therein, a pair of semi-rigid snuffer clips forming part of said series of clips and disposed one on each side of said cigar clip and a pair of cigarette retaining and holding clips also forming part of said series of clips and disposed one on each side of said snuffer clips, and means engaging one of said lower return bends to support said clips when so bent, in an upright position with the remainder of the strip free.

2. A combined cigarette holder and snuffer

comprising a strip of spring metal in ribbon form, said strip being bent at spaced intervals to form substantially U-shaped clips adapted to receive and grip a cigarette therein, said clips including 5 end clips and intermediate clips all extending in a uniform direction, the ends of the strip being free and forming the outer legs of the end clips, and a supporting member attached to the bottom of one of said intermediate clips for holding 10 the remaining clips in an upright position.

3. A combined cigarette holder and snuffer comprising a strip of spring metal in ribbon form, said strip being bent at spaced intervals to form substantially U-shaped clips adapted to receive 15 and grip a cigarette therein, said clips including end clips and intermediate clips all extending in a uniform direction, the ends of the strip being free and forming the outer legs of the end clips, a supporting member and a pivot pin connecting one of said intermediate clips to said 20 supporting member, said pin extending transversely with respect to the legs of the clip to swingably support the clips for movement into a horizontal position.

JOHN T. SAUNDERS.
